[57] CLAIM

The ornamental design for a ball point pen, as shown and described.

DESCRIPTION

FIG. 1 is a perspective view taken from the top and front, showing the ball point pen of my new design;
FIG. 2 is a perspective view taken from the bottom and partially depicting the rear thereof;
FIG. 3 is a front view thereof;
FIG. 4 is a rear view thereof;
FIG. 5 is a right side view thereof;
FIG. 6 is a left side view thereof;
FIG. 7 is a top view thereof;
FIG. 8 is a bottom view thereof;
FIG. 9 is a top plan view of the ball point pen body with the cap member removed for convenience of illustration;
FIG. 10 is a front view, the rear and side views being identical thereto, of the ball point pen of FIG. 9;
FIG. 11 is a front elevational view of the ball point pen cap member with the pen body removed for convenience of illustration; and,
FIG. 12 is a bottom view of the cap of FIG. 11.
